UNITED STATES PATENT OFFICE

2,172,898

TUBE-CLOSING MACHINE

Charles J. Westin, Philadelphia, Pa., assignor to
 F. J. Stokes Machine Company, Philadelphia,
 Pa., a corporation of Pennsylvania

Original application January 21, 1933, Serial No.
 676,911, now Patent No. 2,068,615, dated Jan-
 uary 19, 1937. Divided and this application
 July 16, 1936, Serial No. 90,884

3 Claims. (Cl. 113—54)

This is a division of co-pending application Serial Number 676,911 of Charles J. Westin, filed January 21, 1933 now Patent 2,068,615 issued January 19, 1937.

5 This invention relates to improvements in machinery used for the closing and sealing of the open end of collapsible tubes, and more particularly to the method and mechanism for closing and folding the open end of the tube; the method and means used in crimping and sealing the fold of the closure or seam; and in other features which will be more apparent from the subjoined description.

10 The machine here shown and described is one of the general type of tube closing and sealing machines and it is used only for the purpose of illustrating and describing the principles of the new and useful improvements included in my invention. The principles embodied in my invention can be used to advantage in any type of tube closing and sealing machine. It should also be understood that the mechanism shown may be used as a separate, complete machine for closing and sealing tubes but usually it forms only a part 15 or attachment of a more complicated but complete machine embodying means for conveying, filling, preforming, closing, crimping and ejecting.

15 The purpose of my invention is to provide means for producing a closed tube which will hold a volume of the maximum amount of material possible for a given size of tube.

20 A feature of my invention is the relieved type of closing jaws. Through this novel construction the air, trapped within the tube in making the fold, is permitted to escape. In the old devices the air is compressed within the tube and, after the pressure of the closing jaws is removed, again expands and opens the fold, causing defective tubes.

25 The crimping jaws on this type of machine are provided with a new type of insert or punches. The type of tube closure produced by these new crimping punches is described and claimed in my co-pending application for a patent, Serial No. 641,553, filed November 7, 1932, (now Patent No. 1,989,031, dated January 22, 1935).

30 The type of tube closure and the saving effected by the use of this new and novel invention are described and claimed in my co-pending application for Letters Patent on improvements in Collapsible tubes, filed June 21, 1933, Serial No. 676,912 now Patent 2,053,015 issued September 1, 1936.

35 For a further exposition of my invention refer-

ence may be had to the annexed specification and drawings at the end of which my invention will be specifically pointed out and claimed.

In the drawings:

Fig. 1 is a side elevation of the machine with 5 parts broken away.

Fig. 2 is a detail view in horizontal cross-section on line 2—2 of Fig. 1.

Figs. 3, 4 and 5 are detail views with parts in vertical cross-section of the tube folding and 10 closing mechanism.

Figs. 6, 7 and 8 are respectively side, top and face views of crimping jaw inserts.

As seen in the drawings, and especially in Fig. 1, my machine consists of an idling pulley 1 which may be connected to any suitable source of power. Pulley 2 is fast on shaft 3 by means of which it drives gears 4 and 5. Gear 5 carries a pin 6 thereon which co-operates with the slots in a star or Geneva wheel 7 which is connected 15 to shaft 8 and thereby drives dial 10 through gears 9.

Dial 10 has, as is best seen in Fig. 2, a plurality of openings 11 therein. Openings 11 are adapted to receive tube-cups 12 therein.

As seen in Fig. 1, gear 4 drives gear 24 which in turn drives shaft 25 so that shaft 25 makes two revolutions for each index or movement of dial 10. At its opposite end shaft 25 carries one of a pair of gears 26 which drive stub shaft 27 having a closed cam 28 mounted thereon. Cam 28 contains cam grooves 29 and 30 in it. Roller 31 is mounted in cam groove 30 and actuates rod 32 which is pivotally connected to lever 33. Lever 33 is mounted at an angle to shaft 25 as can be seen from Fig. 1. Lever 33 carries at its opposite end a rod 34 upon which preformer 35 is mounted.

40 Referring to Figs. 1 and 2, there are shown mounted on shaft 25 cams 41 which drive levers 42 which in turn drive the closing and folding jaws 43. In producing this blunt or straight body type of tube closure, I found that there is less room at the top or end of the tube above the contents for the air, which is trapped within the tube as the folds are made therein. The folds, of course, are started from the top or end of the tube, as seen in Figs. 3, 4 and 5, and the tube is lifted for each fold, a new portion being compressed each time a fold is made. When the 45 folds are made very slowly the air has a chance to escape as the walls are compressed but in high speed machinery the time does not permit the air to escape through the very minute space between the walls of the tube. The closing and folding 50

55

jaws 43 are therefore relieved slightly at 44 at their centers so as to provide a passage for the escape of the trapped air and to prevent the compressing of any air within the tubes. This 5 compressed air has a tendency to open the finished fold after the pressure of the jaws 43 is removed.

As seen in Figs. 1 and 2, there is also provided on shaft 25 a cam 45 which drives linked 10 levers 46 which in turn drive the crimping jaws 47. The crimping jaws 41 carry thereon inserts 48 which have indentations or teeth thereon of the type to produce the type of closure called for in my co-pending application for Letters Patent, 15 Serial Number 641,553, filed November 7, 1932 (now Patent No. 1,989,031, dated Jan. 22, 1935). The inserts 48 carry projections 49 thereon which have at their extremities flat or blunt portions 50. The flat or blunt portions may be above the horizontal centers of the inserts as indicated by the 20 axial line 51. As will be seen from Fig. 2, the teeth 49 mesh or interlock so that indentations are formed in the opposite sides of the fold or closure at the end of the tube.

25 As seen in Figs. 1 and 2, cam groove 29 has a roller (not numbered) co-operating with it. This roller is mounted on the end of rod 52, and through rod 52, actuates linkage 53 thereby raising and lowering the ejector or tube lift-out 19.

30 I do not intend to be limited in the practice of my invention save as the scope of the prior art and of the attached claims may require.

I claim:

1. In a tube-closing machine, the combination 35 comprising, means for conveying a plurality of tubes having open ends to be closed, and closing and folding jaws mounted adjacent the path of travel of the open ends of said tubes, said jaws

having a notch or relieved part in and extending across their operative faces in the same direction as the axis of the tube operated upon to provide for the escape of air from said tubes during the closing operation.

5 2. In an automatic tube-closing machine, the combination comprising, a conveyor for transporting a plurality of tubes having open ends to be closed, closing and folding jaws mounted adjacent the path of travel of the open ends of said 10 tubes, said jaws having a notch or relieved part in and extending across their operative faces in the same direction as the axis of the tube operated upon to provide for the escape of air from said tubes during the closing operation, and one 15 means which drives said conveyor and which also reciprocates said jaws relative to each other.

3. In a tube-closing machine, the combination comprising, means for conveying a plurality of tubes having open ends to be closed, closing and 20 folding means including a pair of jaws mounted adjacent the path of travel of the open ends of said tubes, crimping means mounted adjacent the path of travel of said tubes which have been closed and folded, said jaws having a notch or 25 relieved part in and extending across their operative faces in the same direction as the axis of the tube operated upon to provide a passage through the folds for the escape of trapped air within the tube at the closing operation and before crimping, and interlocking teeth formed in the operative faces of said crimping means adapted to engage the closed end of the tube and to form a row of crimps in the center of said 30 folds, thereby pressing the sides of the closure 35 tightly together.

CHARLES J. WESTIN.
